UNITED STATES PATENT OFFICE.

JOHN W. LAMBERT, OF ANDERSON, INDIANA, ASSIGNOR TO THE BUCKEYE MANUFACTURING COMPANY, OF ANDERSON, INDIANA.

SPEED-REGULATOR FOR EXPLOSIVE-ENGINES.

SPECIFICATION forming part of Letters Patent No. 698,405, dated April 22, 1902.

Application filed June 27, 1901. Serial No. 66,232. (No model.)

To all whom it may concern:

Be it known that I, JOHN W. LAMBERT, a citizen of the United States of America, and a resident of Anderson, county of Madison, 5 State of Indiana, have invented certain new and useful Improvements in Sparking Devices for Gas-Engines, of which the following is a specification, reference being had therein to the accompanying drawings, in which—

10 Figure 1 is a vertical sectional view of a four-cycle explosive-gas engine provided with my invention; Fig. 2, a detail plan view of the speed-regulating device; Fig. 3, a vertical section of the same; Figs. 4, 5, 6, and 7, detail views showing the mechanism in the various positions of receiving, sparking, expanding, and exhausting; and Fig. 8 a detail horizontal section through the spark-chamber. Fig. 9 is a detail section of the buffer 15 on the upper section of the valve-rod.

This invention has reference to the class of explosive-gas engines known as "four-cycle" engines; and its special object is to simplify the igniting mechanism and render it wholly 20 inoperative during the time the engine is running at abnormal speed, and the exhaust-valve is therefore held open by the governor mechanism, as more fully hereinafter set forth.

Referring to the drawings by letters, a designates a pinion on the main shaft, which 25 meshes with a gear *b*, journaled on the counter-shaft *c*, attached to the lower part of the engine-cylinder, the proportion between the pinion and the gear being one to two. Attached to the hub of gear *b* is a cam *d*, which is specially formed so as to not only open the exhaust-valve, but also operate the igniter devices. Resting on the cam is an antifriction device, preferably consisting of a roller *e*, 30 which is journaled on a pin carried on the lower end of the vertically-sliding rod *f*, which is, in effect, a part of the exhaust-valve rod and has its upper end guided in a bracket *g*, attached to the engine-cylinder. Directly in 35 vertical alinement with this rod *f* is the depending end of the upper part *f'* of the exhaust-valve rod, this depending end being provided with a spring-actuated buffer-cap *h*, between which and the lower end of the exhaust-chamber is interposed a spring *i*, which

keeps the exhaust-valve normally held to its seat.

Pivotedly connected to the lower section *f* of the exhaust-valve rod is a trip-rod *j*, which extends upward and rests loosely between the flanges of a guide-roller *k*, journaled on a pin carried by the spark-plate *m*. The upper end of the trip-rod *k* is bent laterally, for a purpose hereinafter set forth.

The spark-plate carries the usual stationary electrode *n*, and a movable electrode, which consists of a rock-shaft *o*, extending into the spark-chamber, and provided with the curved arm *p*, which is adapted to make contact with the stationary electrode when said shaft *o* is rocked. The outer end of the rock-shaft *o* is provided with a rigid arm *q*, extending laterally from the shaft, and bearing against this arm is a spring *r*, which tends to normally separate the contacts. Loosely mounted on the shaft *o* is an arm *s*, which extends laterally in the same direction as arm *q* and into the path of the upper end of the reciprocating trip-rod *j*. Between arm *s* and arm *q* is interposed a spring *t*, which tends to separate said arms and to keep arm *s* normally pressed against a stop-pin *u*, fastened in the spark-plate *m* at a point between the guide-roller and the said arm *s*.

When the trip-rod *j* is raised, it engages the end of arm *s* and forces it toward arm *q*. As soon as spring *t* is compressed sufficiently to exert a greater pressure than spring *r* said spring *r* will yield and permit the movable contact to be pressed against the stationary contact. Then as rod *j* continues to reciprocate it will be disengaged from arm *s* by its bent portion coming into contact with the guide-roller *k*, and the instant arm *s* is freed from rod *j* both springs act and quickly separate the sparking-points and return arm *s* to its normal position against the stop *u*.

The cam *d* is provided at almost diametrically opposite points with sparking and exhausting projections, lettered, respectively, *v* and *w*, so that the valve-rod and trip-rod will be reciprocated or raised twice with each revolution of the cam. The cam rotates in the direction of the arrows shown in Figs. 4, 5, 6, and 7; and, as shown, when the roller *e* 100

is approaching the sparking projection *v* the engine is taking in a charge through the gas-valve and the trip-rod is being elevated to bring the contacts together. Then just as the 5 roller passes over the projection *v* the trip-rod is released and a spark is produced; but the rod *f* is not raised high enough by projection *v* to open the exhaust-valve, so that no exhaust can take place on that stroke. 10 Then while the engine is on its working stroke the roller is approaching the enlargement *w*, and when the working stroke is finished the enlargement *w* elevates rod *f* until it comes in contact with the buffer *h* and opens the 15 exhaust-valve and holds it open during the entire exhaust-stroke of the piston. As will be seen, the exhaust-valve is directly below the inlet-valve, so that when it is raised it will come in contact with the inlet-valve and 20 hold the same closed while the engine is exhausting.

The speed-regulating devices consist of a horizontal ring-like frame *a'*, bolted to a lug *b'*, formed on the side of the cylinder just 25 above the boss in which counter-shaft *c* is secured, the rod *f* working in a dovetail notch formed in the outer edge of said frame *a'*. Journaled in the frame *a'* is a short horizontal shaft *c'*, which extends across said frame 30 and is provided at one end, outside of the frame, with a pinion *d'*, which meshes with gear *b*. Pivoted in a slot in the shaft *c'* are the arms of a pair of governor-balls *f''*, and slidingly mounted upon the shaft *c'* is a sleeve 35 *g'*, which is embraced by a bifurcated lever *h'*, pivoted thereto by pivotal screws *i'*. The lever *h'* is pivoted at one end to frame *a'* and at its other end it lies close to and at right angles to rod *f*. The free end of the lever *h'* 40 is connected to the cylinder of the engine by a coil-spring *j'*, which serves to keep the lever normally out of contact with rod *f* and also to keep the sliding sleeve *g'* normally pressed against the arms of the governor-balls. 45 As will be observed, when the speed of the engine increases beyond the normal the governor-balls will force sleeve *g'* outward against the action of spring *j'* until the lever *h'* engages a notch or projection in rod *f* and holds the same up off the cam. 50 In this position the exhaust-valve will be held open and the suction will take place in through the exhaust-passage, the inlet-valve being kept closed. This suction through the exhaust- 55 valve will continue with each exhaust-stroke of the piston until the speed of the engine is reduced sufficiently to permit the governor-arms to resume their normal position and the spring *j'* to withdraw lever *h'* from contact 60 with rod *f*. Thus causing the suction and intake to occur through the exhaust-valve when the speed increases beyond normal effects a large saving of gas, as is obvious.

A very important feature of this engine lies 65 in operating the exhaust-valve and the igniter devices from a single cam having opposite projections, one to operate the igniter and the

other to operate the exhaust-valve, the part of the cam brought into play to operate the igniter being lower than the valve-operating 70 part, so that the igniter devices will be tripped sufficiently in advance of the opening of the exhaust-valve to allow the engine to make its expanding or working stroke. Another feature of importance lies in so connecting the 75 igniter to the valve-rod of the exhaust-valve that when the exhaust-valve is held open during abnormal speed the trip-rod and other parts of the igniter will be wholly at rest, thereby saving in battery-current and also in 80 wear and tear on the parts.

The trip-rod *j* is normally held against guide *k* by a spring *j''*, connecting a lateral lug on its lower end to a stationary part of the engine-frame.

Having thus fully described my invention, what I claim, and desire to obtain by Letters Patent, is—

1. The combination with a gas-engine, of a cam and means for rotating it from the engine-shaft, this cam having sparking and exhausting enlargements respectively at opposite sides, an exhaust-valve and a two-part rod for said valve, means for normally closing the valve, an antifriction device carried by 95 one part of said rod and adapted to bear upon said cam and be operated thereby, igniter mechanism, and a trip-rod adapted to operate the same, said trip-rod being connected to the part of the valve-rod carrying the antifriction 100 device, for the purposes set forth.

2. In combination with a gas-engine, a cam adapted to receive rotation therefrom and to act both as a sparking and an exhausting cam having sparking and exhausting enlargements respectively at opposite sides, the 105 sparking enlargement being lower than the exhausting enlargement, an exhaust-valve having a two-part rod, one part being connected directly to the valve and the other part being adapted to be operated by said cam, igniter devices, and means for operating them by connection directly with the cam-operated part of the valve-rod, for the purposes set forth.

3. In combination with a gas-engine, a cam adapted to serve both as a sparking and an exhausting cam having sparking and exhausting enlargements respectively at opposite sides, means for rotating this cam from the 120 engine, an exhaust-valve having a two-part stem, one part being connected directly to the valve and the other part being operated directly by the cam, igniter mechanism and means for operating it by connection with the 125 cam-operated part of the valve-rod, and speed-regulating devices constructed and arranged to hold the cam-operated part of the valve-rod out of engagement with the cam, the exhaust-valve off its seat and the igniter mechanism out of operation upon abnormal speed.

4. In combination with a gas-engine, an igniter mechanism consisting of a stationary electrode, a movable electrode consisting of

a rock-shaft, extending into the sparking-chamber and provided with a movable contact-arm, an arm rigidly attached to said shaft on its outer end, a loose arm mounted on said shaft adjacent to the rigid arm, a spring bearing against said rigid arm and normally holding the contacts apart, a spring between said two arms, a stop device engaging the loose arm, and a trip-rod adapted to engage the loose arm and force it toward the rigid arm

and thereby bring the contacts together, and means for disengaging said trip-rod from said loose arm.

In testimony whereof I hereunto affix my signature, in the presence of two witnesses, 15 this 17th day of June, 1901.

JOHN W. LAMBERT.
